UNITED STATES PATENT OFFICE.

WILLIAM OEHLMSTROM, OF PARMA TOWNSHIP, CUYAHOGA COUNTY, OHIO.

RADIATOR OR HEATER.

Application filed November 11, 1924. Serial No. 749,164.

To all whom it may concern:

Be it known that I, WILLIAM OEHLMSTROM, a citizen of the United States, residing in the township of Parma, in the county of 5 Cuyahoga and State of Ohio, have invented a new and useful Radiator or Heater, of which the following is a specification.

This invention relates to improvements in radiators or heaters, and more especially to 10 a heater adapted to be arranged adjacent and endwise of a base-board of a wall of a room to be heated by said heater.

One object of this invention is to produce a strong and durable radiator or heater of 15 the character indicated which comprises a substantially horizontally arranged receptacle having a heating-fluid-receiving interior chamber extending endwise of the receptacle.

Another object is to use sheet-metal in the formation of said receptacle, and to adequately reinforce the receptacle externally at points spaced endwise of the receptacle.

Another object is to so construct my improved radiator or heater that the bottom of the hereinbefore mentioned chamber is spaced upwardly from the floor on which the heater is adapted to stand, and more especially to provide the receptacle, adjacent said bottom and externally of said chamber, with two spaced opposite members which extend below said bottom and endwise of the receptacle, and to supply air from the outer sides of one or both of 35 said spaced members to the space formed under said bottom between said spaced members.

Another object is to render my improved radiator or heater suitable for the use of 40 steam or hot water as a heating fluid, and to render the heater reversible side for side and end for end.

Another object is to facilitate the manufacture and assemblage of the component 45 parts of the heater.

With these objects in view, and to attain other objects hereinafter appearing, this invention consists in certain features of construction, and combinations and relative arrangements of parts, hereinafter described in 50 this specification, pointed out in the claims, and illustrated in the accompanying drawings.

In said drawings, Figure 1 is a side elevation of a radiator or heater embodying my invention. Figs. 2 and 3 are, respectively,

a top plan and a bottom plan. Fig. 4 is an end view. Fig. 5 is a vertical transverse section taken along the line 5—5 in Fig. 1. Fig. 6 is a central vertical longitudinal section taken along the line 5—5 in Fig. 2. Fig. 7 is a horizontal section taken along the line 7—7 in Fig. 6. Fig. 8 is a transverse vertical section taken along the line 8—8 in Fig. 6, looking outwardly. Figs. 5, 6, 7 and 8 are drawn on a larger scale than Figs. 1, 2, 3 and 4.

My improved radiator or heater comprises a substantially horizontally arranged receptacle which is oblong in plan and has a 70 heating-fluid-receiving interior chamber 10 extending endwise and substantially from end to end of the receptacle. Said chamber is shown as having a top wall which (see Fig. 6) curves outwardly in cross-section 75 and is formed by the top or central longitudinal member 12 of a substantially horizontally arranged inverted-trough-shaped metal section preferably composed of sheet-metal and extending from end to end of 80 the receptacle and having two spaced opposite side members 13 which are connected together by the member 12 and arranged to form opposite upright longitudinal or side walls respectively of said chamber. 85

The chamber 10 has a bottom 15 arranged between and extending endwise of the side members 13 and spaced, preferably from end to end, upwardly from the bottom edges of said side members, and said chamber has 90 two end upright transverse or end walls 16 formed at opposite ends respectively of said bottom and arranged between the side members 13. The bottom 15 and the end walls 16 preferably comprises a sheet-metal 95 section which is interposed between the side members 13 and bent and disposed as required to form said walls and said bottom. The end walls 16 extend and conform to the top wall 12, and the section forming the 100 end walls and the bottom 15 is brazed or otherwise suitably secured, at and from end to end all of its edges, to the hereinbefore-mentioned inverted-trough-shaped section, so as to form fluid-tight joints between said 105 sections.

The side members 13 of said inverted-trough-shaped section (see Figs. 1, 5, 6 and 8) extend, as at 17, as already hereinbefore indicated, below the bottom 15 from end to 110 end of the receptacle, and therefore the receptacle is provided, adjacent said bottom

and externally of the chamber 10, with two spaced members 17 extending below said bottom and endwise of the receptacle. The side members 13 (see Figs. 3, 6 and 7) preferably extend, as at 18, somewhat outwardly beyond the outer sides of the end walls 16.

The bottom-forming section (see Figs. 1, 3 and 5) is provided, at the outer side of the bottom 15 substantially centrally between the ends of the receptacle, with an internally screw-threaded pipe-connection 20 brazed or otherwise secured to said bottom and preferably arranged centrally between the portions 17 of the side members 13. Said pipe-connection (see Fig. 5) registers with a hole 19 formed in and extending vertically through the bottom 15 and is, therefore, placed in communication with the chamber 10, and said bottom slopes from each end of the receptacle downwardly toward said pipe-connection. Each end wall 16 (see Figs. 1, 4, 6 and 8) is provided, at the outer side of its upper end portion, with an internally screw-threaded pipe-connection 21 brazed or otherwise secured to said wall and preferably arranged centrally between the sides of the receptacle, and said pipe-connection (see Figs. 6 and 8) registers with a hole 22 formed in and extending laterally through said wall, and therefore said pipe-connection is placed in communication with the chamber 10. When hot water is to be used as a heating fluid in my improved radiator or heater, hot-water-feeding pipes (not shown) are placed in communication, at the pipe-connections 21 of the end walls 16, with the chamber 10, and the pipe-connection 20 is placed in communication with a drain-pipe (not shown). When steam is to be employed as a heating fluid in the heater, the pipe-connections 21 are plugged in any approved manner, and the pipe-connection 20 is placed in communication with a pipe (not shown) adapted to be employed both in supplying steam to the chamber 10 and in draining said chamber of water resulting from the condensation of vapor in the chamber.

The hereinbefore-mentioned inverted-trough-shaped section and the bottom 15 are reinforced at points spaced endwise of the receptacle between the pipe-connection 20 and each end of the receptacle, and highly practical reinforcing means for the receptacle comprises two strong metal straps or reinforcing members arranged at opposite ends respectively of the receptacle and two strong metal straps or reinforcing members C arranged between each end reinforcing member B and the pipe-connection 20. Said reinforcing members B and C are spaced endwise of the receptacle, and each of said reinforcing members embraces the inverted-trough-shaped section above the bottom 15 and embraces the lower portions 17 of the

side members 13 of said section below said bottom and participates in the formation of supporting means for the receptacle. Preferably each of said reinforcing members (see Figs. 8 and 9) has a portion 23 straddling and embracing the inverted-trough-shaped section above the bottom 15, and each reinforcing member, below said bottom at each side member 13 of said section, has a portion 24 which overlaps the bottom edge of and embraces the lower portion 17 of said side member 13, and said portion 24 terminates, at the under side of the bottom 15, in an arm 25 projecting, at the inner side of said portion 17 of said side member 13, inwardly and arranged to form a seat for said bottom. The arms 25 of the portions 24 of each reinforcing member are brazed, welded or otherwise secured together or to the bottom 15. It will be observed, therefore, that each portion 24 of each reinforcing member forms a foot adapted to rest on the floor of the room to be heated by my improved radiator or heater.

The space formed under the bottom 15 and between the lower portions 17 of the side members 10 is, of course, open at the ends of the receptacle so that air may enter said space at said ends, and it will also be observed that the bottom edge of the portion 17 of each side member 13 is spaced upwardly from the lower extremities of the adjacent foot-forming portions 24 of the reinforcing members B and C so as to permit the passage of air at said edge into said space from between adjacent reinforcing members. To facilitate the supply of air to the space formed under the bottom 15 between the lower portions 17 of the side members 13, each portion 17 of each of said side members has a row of air-inlets 26 formed at and spaced endwise of its bottom edge between the reinforcing members C. I would also remark that the central or top member 12 of the hereinbefore mentioned inverted-trough-shaped section is shown as provided with a pet-cock 27 at which, when desired, air may be admitted to or permitted to escape from the chamber 10.

What I claim is:—

1. A heat-radiating device comprising an inverted-trough-shaped member which forms the top and side walls of said device, a second member substantially U-shaped and constituting the bottom and end walls of said device, said second member lying within the inverted-trough-shaped member and secured thereto to form a fluid-tight receptacle, and outlet and inlet means for said receptacle to permit passage of a fluid.

2. A heat-radiating device comprising an inverted-trough-shaped member which forms the top and side walls of said device, a second member substantially U-shaped

- and constituting the bottom and end walls of said device and lying within the inverted-trough-shaped member and secured thereto to form a fluid-tight receptacle, outlet and inlet means for said receptacle to permit passage of a fluid, and reinforcing members spaced endwise and arranged externally of and embracing the aforesaid inverted-trough-shaped member and extending under the bottom edges of said inverted-trough-shaped member.
3. A heat-radiating device comprising an inverted-trough-shaped member which forms the top and side walls of said device, a second member substantially U-shaped and constituting the bottom and end walls of said device and lying within the inverted-trough-shaped member and secured thereto to form a fluid-tight receptacle, outlet and inlet means for said receptacle to permit passage of a fluid, and reinforcing members spaced endwise of and embracing the aforesaid inverted-trough-shaped member and having portions thereof arranged to form seats for and to reinforce the aforesaid second member.
4. A heat-radiating device comprising a fluid-tight receptacle oblong in plan, said receptacle having outlet and inlet means permitting passage of a fluid, end walls, a member forming the side walls and top of said receptacle, said member extending beyond the end walls and bottom of the receptacle, and reinforcing members spaced lengthwise of the receptacle and embracing completely the member which forms the top and side walls thereof.
5. A heat-radiating device comprising a fluid-tight receptacle oblong in plan, said receptacle having outlet and inlet means permitting passage of a fluid, end walls, a member forming the side walls and top of said receptacle and extending below the bottom of the receptacle and having lateral air-inlets below said bottom, and reinforcing members spaced lengthwise of the receptacle and embracing completely the member which forms the top and side walls of the receptacle.
6. A heat-radiating device comprising an inverted-trough-shaped member which forms the top and side walls of said device, a second member substantially U-shaped and constituting the bottom and end walls of said device and lying within the inverted-trough-shaped member and secured thereto to form a fluid-tight receptacle, and outlet and inlet means for said receptacle to permit passage of a fluid, the aforesaid inverted-trough-shaped member extending endwise beyond the ends of and below the aforesaid second member.

In testimony whereof, I sign the foregoing specification.

WILLIAM OEHLMSTROM.
